Du Bois, Pa., assignors to Vulcan Soot Blower
Corporation, a corporation of Pennsylvania

Application August 5, 1939, Serial No. 288,486

9 Claims. (Cl. 141—1)

It is essential that cylinder heads for internal combustion engines be thoroughly cleaned before being assembled in their final positions for use, to make certain that all grit and other loose 5 foreign matter be washed away and that none of the oil and chips, resulting from the machining operations, remain. These cylinder heads are commonly made in the form of castings, suitably cored so that, although the interiors are open to atmosphere, pockets are present which will cause liquid or other foreign matter to be retained, to some extent, in any given 10 position of a head.

The object of the present invention is to produce 15 an apparatus which will not only clean the easily accessible surfaces, but which will also effectively clean the more inaccessible interior surfaces.

It is possible to deliver jets of cleaning fluids 20 which will successfully dislodge oil and chips, the only difficulty experienced in a complete cleaning operation being the complete cleaning of the open or partially opened cavities present in the original castings. We have found that 25 if a casting is subjected to jets of cleaning liquids, properly directed, for a short period of time and is then turned over to permit any liquid that has collected therein to run out, a large portion of the foreign matter which it is 30 desired to eliminate will be carried away with the liquid. As there may not be any single position of the casting that will permit a thorough cleaning by a single emptying of the fluid contents, it is usually necessary to repeat the operation 35 of delivering jets and turning the casting over. In accordance with our invention, we make use of this principle of successive emptying of the cavities in a cylinder head, employing 40 a sufficient number thereof to provide a sufficient factor of safety against leaving any grit, chips or other objectionable foreign matter within or upon the head.

The various features of novelty whereby our 45 invention is characterized will hereinafter be pointed out with particularity in the claims; but, for a full understanding of our invention and of its objects and advantages, reference may be had to the following detailed description taken 50 in connection with the accompanying drawings, wherein:

Figure 1 is a side view of an apparatus embodying the present invention in a preferred form, parts being broken away to expose other parts; 55 Fig. 2 is a fragmentary view, on a larger scale,

illustrating a fragment of a cylinder head and the portions of the holder therefor immediately adjacent thereto; Fig. 3 is an elevational view illustrating the motor driven controller; Fig. 4 is a plan view of the apparatus shown in Fig. 1, the casing or housing being in section, and the receiving table for the work being omitted; Fig. 5 is a section on an enlarged scale taken on line 5—5 of Fig. 1, showing only the holder for the cylinder heads and a fragment of the ejector; Fig. 6 is a view showing in section the main valve for controlling the cleaning fluid, together with the pilot valve for controlling the main valve; and Figs. 7, 8 and 9 are wiring diagrams illustrating, respectively, the positions of the parts when the apparatus is idle, immediately after a controlling switch or push button has been operated and released and during the remainder of a cycle that again terminates with the apparatus in an idle state.

Referring to the drawings, 1 represents a housing or casing of suitable size, there being in front of the same a table 2; the housing being closed at the front, back and sides except for the presence of a shallow opening 3 in the front wall at the top of and extending across the width of the table; this opening being high enough to permit a cylinder head lying flat on a table to be pushed into the opening and into the casing.

Within the casing is a holder for containing a plurality of cylinder heads at one time. This holder is carried by a heavy horizontal shaft 4 extending from front to rear and having suitable bearings in the front and rear walls. This shaft may conveniently be in the form of a sturdy tube into the rear end of which cleaning fluid is introduced, as will hereinafter be explained.

Surrounding and fixed upon the shaft 4 are two long box-like members 5 and 6, respectively, nested one within the other; the outer member being slightly wider than the width of a cylinder head to be treated, and being also somewhat longer than such a head. The inner member 5 is shorter and has substantially narrower sides than the outer member. Each of these two members has its own rear wall, but they may be closed at the front by a single wall common to both. In this way there is left a substantial unobstructed space within the rear end of the outer member 6 around the supporting shaft, while there is a shallow space or chamber between the longitudinal walls of said members. That part of the shaft within the space between the rear

end walls of the members 5 and 6 contains large openings 7 through which water or other cleaning fluid may be discharged and completely fill all of the space between the exterior of the inner member 5 and the surrounding member.

Each longitudinal wall of the outer box-like member 6 is provided with a pair of ribs 8 extending throughout the entire length thereof along its margins. Each of the longitudinal walls 10 of the member 6 is provided with a group or groups of jetting orifices 9 so disposed that when a cylinder head, such as indicated at A, is properly set upon the ribs rising from that wall, there will be a jet opening opposite every hole or opening in the cylinder head into which cleaning fluid is to be discharged.

Surrounding the box-like structure just described is a cage shown as comprising a rear frame-like member 10 and a front frame-like member 11. Both of these frames may be in the form of squares having four additional narrow sides instead of corners. As best shown in Fig. 5, these frames may conveniently be supported from the member 6 by means of spoke-like arms 12 extending radially of the structure from the four corners of the member 6 to the narrow side sections of the frames. Cooperating with the frames are eight longitudinal angle irons 14 arranged in pairs, each of which lies outwardly from a pair of ribs 8 on the member 6. The parts are so proportioned that a cylinder head is a sliding fit between each pair of ribs and the corresponding pair of angle irons; one flange of each angle iron lying outwardly from one of the broad faces 35 of the head and the other overlapping one of the long side or edge faces, so that each pair of angle irons serves not only to hold a head against the cooperating ribs, but also prevents the head from shifting laterally. The forward ends of the angle irons 14 are bent away from the longitudinal axis of the holder to provide a flaring mouth or entrance to the latter. In other words, when the holder is in the position shown in Fig. 1, a cylinder head on the table 2 can easily be slid 40 upon the lower pair of angle irons 14 because the adjacent ends 15 of the lower angle irons are curved downwardly and constitute short inclines or skids to raise the advancing end of a head pushed against the same.

50 In order properly to register the cylinder heads in the lengthwise direction, the rear frame 10 may conveniently be composed of a structural angle iron, one of whose flanges is vertical, as best shown in Fig. 2, while the other flange 55 extends horizontally in the forward direction from the outer edge of the vertical flange. By providing the vertical flange with set screws 16, extending in the longitudinal direction, from the rear thereof, the forward ends of the set screws 60 may serve as stops to limit the rearward movement of the heads when they are inserted in the holder; thus providing adjustable stops to secure accurate registration between the jetting orifice and the openings in the heads into which 65 they are to discharge.

The heads are inserted in the holder, as heretofore explained, by sliding them, one at a time, into a receiving compartment when the latter is in its lowermost position, just behind the receiving table. Each head is also adapted to be removed from the holder when it is brought back again to the starting position. In order to facilitate such removal, there is provided an ejecting device comprising a curved finger 17 carried on 70 the end of a rocker arm 18 fixed to a transverse

shaft 19 suitably supported below the casing or housing 1. The shaft 19 has a second short arm 20 which is connected by a rod 21 to one arm of a lever 22 mounted at the front of the structure below the receiving table; the other arm 24 of this lever extending outwardly beyond the front end of the table, where its free end may be grasped for the purpose of pulling up on the same. When the lever handle is pulled up, it causes the rocker arm 18 to be swung in the 10 counter-clockwise direction, as viewed in Fig. 1, and the ejecting finger 17 to be forced against the end of the cylinder head if there be one in the lower compartment of the holder. In this manner the cylinder head may be pushed partly out 15 of the holder, until it extends well out over the table and can easily be grasped and pulled out the rest of the way.

It will be seen that whenever the holder is filled with cylinder heads and water or other cleaning fluid, under pressure, is delivered to the tubular shaft 4, jets of this fluid will be discharged into the drilled holes and other openings of each head. We have found that by turning the holder step by step, in order to bring a new compartment into 25 receiving or discharging position at the end of each step, each head is permitted to rest long enough in a plurality of different positions to insure perfect draining. We have therefore provided means for supplying the cleaning fluid, revolving the holder step by step, and shutting off the flow of cleaning fluid whenever the holder has turned through a complete step. In the arrangement shown, the cleaning fluid is delivered through a large supply pipe 23 behind the casing 35 or housing; this pipe having at the lower end a pipe 25 in which the hollow end of the shaft 4 is rotatably supported. The supply pipe contains a master valve housed in a valve casing 27, this valve being controlled by a suitable pilot valve. 40 This part of the apparatus is exactly like the corresponding valve mechanism in our prior application, Serial No. 183,760, for Automatic motor-block cleaner. This valve mechanism comprises a spring-closed master valve 23 which is adapted 45 to be opened by the pressure of the cleaning fluid when a pilot valve 29 is actuated to place the space behind the master valve in communication with atmosphere, in order to permit the fluid pressure to overcome the force of the spring that 50 normally holds the master valve closed. Cleaning fluid enters the righthand end of the valve casing 27, as it appears in Fig. 6, and, when the pilot valve is in the position illustrated in this figure, fluid may flow from the righthand side of the valve casing 27 through the pipe 91, through the valve casing 29, and back through pipe 92 to a point above the piston valve 28, whereby the pressure of the cleaning fluid assists the spring 93 in holding the valve 28 closed. When the movable member 94 of the pilot valve is pushed inwardly, namely toward the right in Fig. 6, communication between the pipes 91 and 92 is interrupted, and the pipe 92 is adapted to vent to atmosphere 60 through a small port 95. Consequently, only the spring now tends to hold the main valve closed, whereas the pressure of the cleaning fluid against the main valve in a direction to open the same is sufficient to overcome the spring and the main valve thereupon opens. As in the aforesaid application, the pilot valve has a stem 30 which may be pushed in by means of an arm 31 on a rock shaft 32; the free end of the arm being adapted to be pressed against the end of the valve stem when the rock shaft is rotated in one direction. 65 70 75

The rock shaft is actuated and the tubular shaft is rotated by means of an electric motor 34. This motor is connected to a suitable speed-reducing device 35 by means of a clutch 36 normally held open by a spring 37 and adapted to be closed by an electromagnet 38. From the output shaft of the speed-reducing device there extends an endless sprocket chain 39 that runs over a sprocket wheel on a shaft 40 whose axis lies in the same vertical plane as the axis of the hollow shaft 4, but at a lower level. On the shaft 4, just in front of the head 26, is a large gear wheel 41 which meshes with a pinion 42 on the forward end of the shaft 40. On the other end of the shaft 40 is a gear wheel 44 meshing with a gear wheel 45 on a shaft 46 which may be termed the control shaft for stopping and starting the flow of cleaning fluid and for causing the motor to stop whenever the holder for the cylinder heads must come to rest.

Since the holder for the cylinder heads is shown as being four-sided or having four compartments, it should stop four times during each revolution. Furthermore, since the discharge of cleaning fluid should cease whenever the holder is at rest, the pilot valve should be permitted to close four times during each revolution of the holder. If the holder had a different number of sides or compartments, it would be brought to rest a corresponding number of times during each revolution and the pilot valve would be permitted to close a similar number of times. Therefore, in the arrangement shown, assuming the speed ratio between the shaft 40 and the shaft 4 to be four to one, the speed ratio between the shaft 40 and the shaft 46 should be one to one. In other words, the control shaft completes a cycle for each quarter turn of the holder.

As best shown in Fig. 3, the control shaft 46 has thereon a disk 47 in the periphery of which is a notch 48. The rock shaft 32 is provided with an arm 49 on the end of which is a roller 50 adapted to ride on the periphery of the disk and, when the notch 48 comes into registration therewith, to drop into this notch. Assuming that when the roller 50 is in the notch 48, the pilot valve is in its inoperative position, so that the main valve is closed, it will be seen that the supply of cleaning fluid is shut off at every quarter turn of the cylinder head holder. It is necessary that the motor stop at the same time that the holder for the cylinder head stops and the cleaning fluid is shut off. This may conveniently be accomplished by placing adjacent to the disk 47 a suitable switch 51 of the type that is normally closed but may be opened by pressing a handle or other member which, in the present instance, is shown as taking the form of a roller 52. Mounted on the shaft 46 beside the disk 47 and in the plane of the roller 52, is a radial arm 54 of such length and so disposed angularly over its shaft that the roller 52 is pressed down thereby at the instant that the roller 50 drops into the notch 48. Consequently, the closing of the main valve and the cutting off of the power take place simultaneously. We have referred heretofore to the stopping of the motor but, as shown, it is preferable that the motor be kept running and that the cutting off of the power to drive the other movable mechanisms be effected by opening the clutch.

After the holder for the cylinder heads has stopped and the supply of cleaning fluid shut off, operations may again be caused to begin by actuating a suitable manual controller, conveniently

a push button. The switches, aside from the push button and the switch 51, forming part of the control system for the solenoid 38, are contained in two switch boxes 55 and 56. The entire control system is illustrated diagrammatically in Figs. 7 to 9, inclusive. Referring to these figures, it will be seen that the motor current is supplied through three line wires B, C and D, a suitable circuit breaker 57 serving to close and open the motor circuit. Current for energizing the solenoid 38 is obtained by connecting the solenoid across the lines B and D. In the solenoid circuit is a switch 59 carried upon a movable rod-like member 60 fixed to the core of a solenoid 61; this switch, though normally open, is closed upon energization of the solenoid 61. Three other switches 63, 64 and 65 are also mounted on the member 60; these switches, also, being normally open. There is a second switch device, more or less similar to the one just described, comprising a movable supporting rod 66 carrying the movable members of three switches 67, 68 and 69, the rod being attached to the core of a solenoid whose coil is indicated at 70. These two electrically-operated switches are controlled by the switch 51 and by a manually-operable switch, illustrated as taking the form of a push button 71. It will be seen that whereas the switches 67 and 68 are normally open, the switch 69 is normally closed.

With the parts in the positions illustrated in Fig. 7, it will be seen that upon pressing the push button, current flows from the secondary of the transformer 58 through a wire 73, through the push button, through the switch 69, through a wire 74, through the solenoid 61, and thence back to the opposite end of the circuit through a wire 75. Thus the solenoid 61 is energized, and the switches 59, 63, 64 and 66 are closed. The closing of the switch 59 causes the solenoid 38 to be energized and the clutch 36 to be thrown in, so that the holder for the cylinder heads and the control shaft 46 begin to turn. This condition is illustrated in Fig. 8, except that the push button is shown open. The opening of the push button, immediately after the solenoid 61 has been energized, is permitted by reason of the fact that as soon as the switches associated with the solenoid 61 are closed, current flows through the wire 73, 40 wire 76, wire 77, switch 65, wires 78 and 88, 50 switch 69, wire 74, solenoid 61 and through the wire 75, thus completing the circuit through the secondary of the transformer. When the motor has turned far enough to permit the switch 51 to close, as shown in Fig. 9, the energizing circuit 55 for the solenoid 70 is established as follows: through wires 73 and 76, wire 80, switch 51, wire 81, switch 63, wire 82, solenoid 70 and wire 83 to wire 75; the secondary of the transformer connecting the wires 73 and 75. Since the energization of the solenoid 70 causes the switch 69 to open, a new circuit must be established for the solenoid 61. This circuit can be traced as follows, from the secondary of the transformer through wires 73, 76, 80, switch 51, wire 85, switch 65 68, wire 86, switch 64, wire 74, solenoid 61 and wire 75, back to the other terminal of the transformer. Therefore, while the holder for the cylinder heads is being turned from one position to the next, the circuit for the solenoid 61 still flows 70 through one of the switches actuated by the solenoid 70, although now it is a switch that is normally open and is closed only when the solenoid 70 is energized; and, since the switch 69 is now open, the energization of the solenoid 61 depends 75

upon the switch 51 remaining closed. As a result, after the holder for the cylinder heads has completed a quarter turn and the control shaft 46 has made a complete turn, bringing it into the position shown in Fig. 3, and the switch 51 is again opened, both solenoids 61 and 70 are de-energized and the parts are restored to the positions illustrated in Fig. 7, so that the holder for the cylinder heads remains at rest until the push button is again pressed. It will be seen that while the solenoid 61 becomes de-energized just as soon as the switch 51 is opened, the solenoid 70 remains energized as long as the switch 65 is closed, so that it does not become de-energized until after 10 all of the switches 59, 63, 64 and 65 have opened; this being for the reason that after the solenoid 15 70 has once been energized, current may flow from the secondary of the transformer through wires 73 and 76, through wire 77, switch 65, wires 20 78 and 88, switch 67, wire 89, solenoid 70, wires 83 and 75 to the other terminal of the secondary. In Figs. 7, 8 and 9 the circuit breaker 57 is shown open but it will be closed whenever it is desired to operate the cleaning apparatus.

25 It is believed that the operation of the cleaning apparatus has been described in connection with the foregoing detailed description. Briefly stated, however, assuming that the parts are at rest in the positions illustrated in Figs. 1 to 6 of 30 the drawings, and that there is a cylinder head resting on the table 2, this head may be pushed into the casing or housing, through the opening 3 and upon the lower pair of angle iron rails, until it engages the adjustable stop 16 at the 35 rear end of the holder. It should be noted that the opening 3 is partially closed, by a rubber flap 90, as best shown in Fig. 1, which flap yields before the advancing cylinder head and drops back again after the head has entered the housing. The head being properly located in the 40 holder, the operator presses the push button 71, causing the drive mechanism to be clutched to the motor. Thereupon, the holder starts to rotate, and the valve controlling the admission 45 of cleaning fluid is opened. This condition is maintained until the holder has completed a quarter turn, whereupon the clutch is thrown out and the valve closed. The operator may now 50 insert another cylinder head in the compartment of the holder which is at the bottom, provided that this compartment contains no head. Should there be a cylinder head present in this compartment, however, the operator pulls up on the lever handle 24, causing this head to be partially 55 pushed out of the holder and housing, so that it may be completely removed before a fresh cylinder head is inserted. If this process is continued, the holder turning step by step through successive angles of 90°; the fourth step brings 60 the head back to the starting point clean and ready to be taken out of the holder. It will be seen that during the movement of each head into each new position, it is being continuously subjected to the action of jets of cleaning fluid; 65 the jetting being interrupted whenever the head comes to rest. Since each rest period is occupied by the acts of taking out a cleaned head and the insertion of one that is to be cleaned, after the holder has once been filled, there is ample time 70 for all of the fluid that can escape from the head in any one of its several positions to drain before a new jetting onset or attack begins. It will further be seen that while the starting of the apparatus is controlled manually, the stopping 75 is done automatically; thus avoiding any waste

of time in stopping, and permitting the workman to regulate the periods of rest in accordance with the speed at which he can make a change of cylinder heads in the holder.

While we have illustrated and described with 5 particularity only a single preferred form of our invention, we do not desire to be limited to the exact structural details thus illustrated and described; but intend to cover all forms and arrangements which come within the definitions of 10 our invention constituting the appended claims; and, when we refer to a "cylinder head", we intend to include other objects which may be treated in a machine or apparatus of the type disclosed.

15 We claim:

1. In combination, means to support a plurality of cylinder heads and turn them step by step about a horizontal axis and bringing them to rest at the end of each step, and means for automatically discharging jets of cleaning fluid against said heads while they are moving and interrupting the jetting during the times when the heads are at rest.

2. In combination, means to support several 25 cylinder heads in distributed relation about a horizontal axis, turn them in unison about said axis through steps whose angular lengths correspond to the angular distances between the heads, and cause them to come to rest at the end 30 of each step; and means automatically to subject each head to the action of jets of cleaning fluid while it is moving and to discontinue the jetting while the heads remain stationary.

3. In combination, a holder for cylinder heads 35 rotatable about a horizontal axis and having a plurality of compartments for individual heads distributed about said axis, means on the holder to discharge jets of cleaning fluid toward the heads, means to turn the holder, means to supply 40 cleaning fluid to the holder, and a control system to cause the holder to turn through a predetermined fraction of a revolution and come to rest and the jets to be active while the holder is turning and inactive while the holder is stationary.

4. In combination, a horizontal rotatable shaft, a long, box-like member surrounding and fixed to the shaft, said member having jetting orifices in each of its long faces, means to hold a cylinder 50 head on and in spaced relation to each of said faces, means to turn said member through steps having angular lengths equal to the angular widths of said faces and cause it to come to rest at the end of each step, and means to deliver 55 cleaning fluid, under pressure, into the interior of said member while said member is turning and to shut off the supply of fluid while said member is at rest.

5. A holder for cylinder heads to be cleaned 60 comprising a box-like member having a central tubular shaft, a filler within said member blocking off all the space therein except at one end and adjacent to the side walls parallel to the shaft, said shaft having openings through the 65 wall thereof into the free end space in said member, and said side walls having therein jetting openings to cause jets of cleaning fluid to be discharged therethrough, whenever such fluid, under pressure, is delivered into the interior of the 70 hollow shaft.

6. In a holder for cylinder heads to be cleaned, a horizontal tubular shaft, a series of hollow supports for cylinder heads distributed about and extending lengthwise of and in fixed relation to 75

the shaft, the interiors of said supports being in communication with the interior of said shaft to receive cleaning fluid from the latter, pairs of guides lying outwardly from and parallel to said supports, means securing said guides to said supports in a manner to leave an unobstructed space between the ends of the guides and the supports at one end of the holder for the entrance of cylinder heads, each pair of guides being adapted to overlie a cylinder head on the corresponding support and overlap the side edges of such heads to hold the latter in place in all angular positions of the shaft, and means on said supports to direct jets of cleaning fluid against cylinder heads in the holder.

7. In a cleaning apparatus for cylinder heads, a casing, a receiving table in front of the casing; the casing having just above the table an opening only sufficiently wide and high to permit a cylinder head to be slid from the table into the casing, a horizontal shaft within and extending from the front of the casing directly above said opening to the rear of the casing, and a holder for cylinder heads on the shaft including a plurality of pairs of flanged guide rails distributed about and parallel to the shaft at such radial distance therefrom that they may be brought successively into the plane of the table with their flanges directed upwardly to engage opposite edges of a cylinder head lying thereon, and means on the holder to discharge jets of cleaning fluid against cylinder heads positioned therein.

8. In a cylinder head cleaning apparatus, a holder for a plurality of cylinder heads rotatable about a horizontal axis and having a series of individual head-receiving compartments distrib-

uted about said axis, jetting means on said holder to discharge cleaning fluid against heads positioned therein, a drive shaft, a control shaft, driving connections from the drive shaft to cause the holder to turn through an angular distance equal to the angular distances between said compartments while the control shaft makes a complete revolution, means controlled by the control shaft to deliver fluid under pressure to the jetting means except when the control shaft is in a given angular position, a control system for causing the drive shaft to start and stop, said system including a manual controller to cause the drive shaft to start and a controller actuated by said control shaft upon reaching said given position to cause the drive shaft to stop.

9. In a cleaning apparatus for cylinder heads, a casing, a receiving table in front of the casing; the casing having just above the table an opening only sufficiently wide and high to permit a cylinder head to be slid from the table into the casing, a horizontal shaft within and extending from the front to the rear of the casing, and a holder for cylinder heads on the shaft including a plurality of pairs of flanged guide rails distributed about the shaft at such radial distance therefrom that they may be brought successively into the plane of the table with their flanges directed upwardly to engage opposite edges of a cylinder head that is pushed rearwardly into the casing from the table, means on the holder to discharge jets of cleaning fluid against cylinder heads positioned therein, and means to move a cylinder head in the holder forwardly to the table.

FRED C. AREY.
